UNITED STATES PATENT OFFICE.

OTTO EMEL ANDERSEN, OF HARRIS, IOWA.

ADJUSTABLE WAGON-SEAT.

1,158,953.

Specification of Letters Patent.

Patented Nov. 2, 1915.

Application filed March 20, 1915. Serial No. 15,748.

To all whom it may concern:

Be it known that I, OTTO E. ANDERSEN, a citizen of the United States, residing at Harris, in the county of Osceola and State of Iowa, have invented certain new and useful Improvements in Adjustable Wagon-Seats, of which the following is a specification.

The present invention relates to certain new and useful improvements in wagon seats, and has for its object to provide a device of this character which embodies novel features of construction whereby the elevation of the seat can be readily adjusted and the seat lowered into the wagon box in windy or stormy weather.

Further objects of the invention are to provide a device of this character which is comparatively simple and inexpensive in its construction, which can be readily applied to any wagon box, which can be easily and quickly raised and lowered and locked at any desired elevation, and which provides a comfortable seat for the driver.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a transverse sectional view through a wagon box provided with an adjustable seat constructed in accordance with the invention, the said seat appearing in front elevation and being shown by full lines in a raised position and by dotted lines in a lowered position. Fig. 2 is a horizontal sectional view on the line 2-2 of Fig. 1, looking in the direction of the arrows. Fig. 3 is a detail view of the finger controlled latch member. Figs. 4 and 5 are detail views.

Corresponding and like parts are referred to in the following description and indicated in all the views of the drawings by the same reference characters.

Specifically describing the present embodiment of the invention, the numeral 1 designates the seat proper, which may be of any conventional construction and is shown in the present instance as provided with a back 2. Arranged under the seat 1 and

spaced therefrom is a seat supporting frame A, said frame including the longitudinal bars 3 connected at points adjacent the ends thereof by the end cross bars 4, and also connected at their middle points by an intermediate cross bar 5. Elliptic springs 6 of the usual construction are interposed between the ends of the seat 1 and the seat supporting frame A. The upper halves of the elliptic springs are secured to the seat by suitable fastening members such as the bolts 7, while the lower halves thereof are secured to the end cross bars 4 of the seat supporting frame A by suitable fastening members such as the bolts 8, blocks 9 being shown as fitted between the two halves of each of the springs and the respective members to which they are bolted.

The extremities of the longitudinal bars 3 of the seat supporting frame A are provided with extension plates 15 having a sliding engagement with vertical guide strips 10 which are fitted against the inner faces of the sides of the wagon body B. In the present instance the guide strips 10 are shown as having a substantially cruciform cross section, one of the ribs of each of the guide strips being provided with notches 11 adapted to coöperate with latch bolts C upon the seat supporting frame A to lock the seat in an adjusted position. The ends of the extension plates 15 are slotted at 12 to receive the guide strips 10, the sides of the slots being notched at 12^a to receive the side ribs of the guide strips.

A spring actuated latch bolt C is mounted upon each end of the seat supporting frame A. These latch bolts C have a substantially U-shaped formation, the arms 14 thereof being parallel and being each slidably mounted within a keeper 16 applied to the extension plate 15 at a point adjacent the inner end of the slot 12, and a guide member 17 disposed at the rear end of the extension plate 15 and formed in the present instance by bending the same outwardly. These extension plates 15 may be rigidly secured to the ends of the longitudinal bars 3 in any suitable manner as by means of the bolts 18. The closed inner ends of the U-shaped latch bolts C are provided with longitudinally disposed crimped portions forming rearwardly projecting arms 19. These rearwardly projecting arms 19 upon the two latch bolts C are offset in opposite directions from the longitudinal axis of the seat sup-

porting frame A, and are pivotally connected at 20 to opposite ends of an operating lever 21 which is mounted upon the intermediate cross bar 5 of the frame A and is pivotally connected thereto at its middle point by means of a pivot bolt 22.

That end of the operating lever 21 extending toward the front of the seat 1 has a finger piece 24 pivotally connected thereto 10 so as to swing vertically toward and away from the seat supporting frame A. A spring strip 25 normally swings the finger piece 24 upwardly into a yielding engagement with the frame A. A keeper 26 receives the finger piece 24 so as to limit the downward swinging movement thereof and also coöperate therewith to limit the lateral swinging movement of the main lever 21. A suitable finger hold 27 may be applied to the finger piece 24, and the latter is also provided with an upwardly projecting stud 28 adapted to engage an opening 29 to lock the latch bolts C in a retracted position, and also to slip over the inclined teeth 30 so as to coöperate 20 therewith to prevent the latch bolts from being accidentally withdrawn a sufficient amount to release the seat after the seat has once been adjusted.

The noses of the latch bolts C are preferably beveled at 14° so as to coöperate in the most effective manner with the notches 11 of the vertical guide strips 10, and each of the arms 14 of the latch bolts C is provided with a spring 31 normally tending to project the latch bolt into operative position. These springs 31 are shown as surrounding the arms 14 and interposed between the guide members 17 and washer members 32 which are held in position by suitable means 30 such as the cotterpins 33. These springs 31 hold the latch bolts yieldingly in a projected position and in order to retract the latch bolts it is necessary to swing the finger piece 24 down and disengage the stud 28. 40 from the inclined teeth 30 preparatory to swinging the main lever 21 laterally. When the latch bolts have been retracted they can be held in such position by causing the stud 28 of the finger piece to engage the opening 29, although as soon as the said stud 28 is disengaged from the opening 29 the springs 31 will force the latch bolts into operative position, the stud 28 slipping over the inclined teeth 30 and coöperating therewith to 50 prevent backward movement of the locking bolts. Owing to this construction no amount of jolting or jarring as the vehicle passes over rough roads will ever result in the latch bolts C becoming disengaged from the notches 11 of the guide strips 10 and permitting the seat to drop.

The guide strips 10 are shown as arranged in pairs, one pair being applied to each side of the wagon box B. As previously explained, the guide strips preferably have a

cruciform cross section, the rear ribs thereof being connected at their lower ends by the transverse strips 34, while the upper ends thereof are secured to hangers 35 adapted to hook over the upper edges of the sides 70 of the wagon box. The guide strips are thus connected to the hangers in such a manner that they can be detachably applied to the sides of the wagon box and moved back and forth thereon into any desired position. 75

With the foregoing construction it will be obvious that by retracting the latch bolts C the seat can be raised and lowered for the purpose of setting it at any desired elevation. After the seat has been properly adjusted it is merely necessary to release the finger piece 24 and permit the spring actuated latch bolts to be moved outwardly so as to engage the nearest set of notches 11 upon the guide strips 10. This adjustment 80 of the seat can be very quickly accomplished and admits of the seat being lowered into the wagon box in stormy and rainy weather so as to protect the driver as much as possible. The cruciform cross section of the 85 guide strips 10 enables them to interlock with the slots in the extension plates 15 so that there is no danger of the guide strips becoming disengaged from the guide slots by a spreading of the sides of the wagon 90 box or the like. This cruciform cross section of the guide strips also gives them great strength for the amount of material employed, since the longitudinal side ribs serve as reinforcing means. 100

Having thus described the invention, what I claim as new and desire to secure by Letters Patent, is:—

1. An adjustable wagon seat including vertically disposed notched guide strips applied to the wagon box, a seat supporting frame slidably mounted upon the guide strips, a seat carried by the seat supporting frame, oppositely facing latch bolts mounted for engagement with the notched guide strips to 105 lock the seat supporting frame in an adjusted position, springs normally tending to move the latch bolts into operative position, a main lever having an operative connection with the latch bolts for simultaneously retracting the same, a finger piece hinged to the main lever so as to swing toward and away from the seat supporting frame, a spring normally tending to swing the finger piece toward the seat supporting frame, and means coöperating with the finger piece to 110 lock the latch bolts in a projected position. 115

2. An adjustable wagon seat including vertically disposed notched guide strips applied to the wagon box, a seat supporting frame, a seat mounted upon the seat supporting frame, extension plates applied to the seat supporting frame and slidably engaging the guide strips, latch bolts slidably mounted upon the extension plates for engagement 120

with the notched guide strips to lock the seat supporting frame in an adjusted position, and means for simultaneously retracting the latch bolts to adjust the position of the seat supporting frame.

3. An adjustable wagon seat including vertically disposed guide strips applied to the wagon box, a seat supporting frame, a seat mounted upon the seat supporting frame, extension plates applied to the seat supporting frame and slidably engaging the guide strips, latch bolts slidably mounted upon the extension plates and adapted to engage the notched guide strips to hold the seat supporting frame in an adjusted position, springs normally tending to project the latch bolt into operative position, a main lever having an operative connection with the latch bolts for simultaneously moving the same, a finger piece for manipulating the main lever, and means coöperating with the finger piece to lock the latch bolts in a retracted position.

4. An adjustable wagon seat including vertically disposed guide strips applied to the wagon box, a seat supporting frame, a seat mounted thereon, a pair of extension plates applied to each end of the seat supporting frame and slidably engaging the guide strips, a U-shaped latch bolt at each end of the seat supporting frame, the arms of the U-shaped latch bolts being slidably mounted upon the extension plates so as to engage the guide strips to lock the seat supporting frame in an adjusted position, a main lever connected to the U-shaped latch bolts so as to simultaneously manipulate the same, springs normally tending to hold the latch bolts in operative position, and means for operating the main lever to control the latch bolts.

5. An adjustable wagon seat including vertically disposed notched guide strips applied to the wagon box, a seat supporting frame, a seat mounted thereon, extension plates applied to opposite ends of the seat supporting frame, the outer ends of the extension plates having a sliding engagement with the notched guide strips while the inner ends thereof are bent outwardly to provide guide members, keepers applied to the extension plates, latch bolts slidably mounted within the keepers and guide members of the extension plates so as to engage the notched guide strips to lock the seat supporting frame in an adjusted position, a main lever having an operative connection with the latch bolts, and yielding means normally tending to move the latch bolts into a projected position.

6. An adjustable wagon seat including vertically disposed notched guide strips applied to the wagon box, a seat supporting frame, a seat mounted thereon, a pair of extension plates applied to opposite ends of

the seat supporting frame, the outer ends of the extension plates having a sliding engagement with the notched guide strips while the inner ends thereof are bent outwardly to provide guide members, keepers applied to the extension plates, a U-shaped latch bolt mounted upon each end of the seat supporting frame, the arms of the latch bolts being slidable within the keepers and guide members of the extension plates and the ends thereof being adapted to engage the notched guide strips to lock the seat supporting frame in an adjusted position, a main lever having an operative connection with the inner ends of the U-shaped latch bolts for simultaneously moving the latch bolts into and out of operative position, yielding means normally tending to project the latch bolts into operative position, and means for manipulating the main lever.

7. An adjustable wagon seat including vertically disposed notched strips applied to the wagon box, a seat supporting frame, a seat mounted thereon, a pair of extension plates applied to each end of the seat supporting frame, the outer ends of the extension plates having a sliding engagement with the notched guide strip while the inner ends thereof are bent outwardly to provide guide members, keepers applied to the extension plates, oppositely facing U-shaped latch bolts mounted upon the ends of the seat supporting frame, the arms of the U-shaped latch bolts being slidable within the keepers and guide members of the extension plates and being adapted to engage the notched guide strips to support the seat supporting frame in an adjusted position, springs engaging the latch bolts and normally tending to project the same into operative position, a main lever having an operative connection with the latch bolt for simultaneously moving the same into and out of operative position, a finger piece hinged to the main lever so as to swing toward and away from the seat supporting frame, and means coöperating with the finger piece to lock the latch bolts in a projected position.

8. An adjustable wagon seat including vertically disposed guide strips of substantially cruciform cross section applied to the wagon box, a seat supporting frame, a seat mounted thereon, means upon the seat supporting frame for slidably engaging the guide strips, and means for locking the seat supporting frame in an adjusted position.

9. An adjustable wagon seat including vertically disposed guide strips of substantially cruciform cross section applied to the wagon box, a seat supporting frame, a seat mounted thereon, extension plates applied to the seat supporting frame, the ends of the extension plates being slotted and the sides of the slots being notched so as to slidably

receive the cruciform guide strips, and means for locking the seat supporting frame in an adjusted position.

10. An adjustable wagon seat including a pair of vertically disposed guide strips of cruciform cross section applied to each side of the wagon box, hangers carrying the guide strips and adapted to fit over the upper edges of the sides of the wagon box, a seat supporting frame, a seat mounted thereon, extension plates applied to the seat supporting frame and provided with slotted ends slidably receiving the guide strips, latch means upon the seat supporting frame 10 for engagement with the guide strips to lock the seat supporting frame in an adjusted position, and means for controlling the latch means.

11. An adjustable wagon seat including vertically disposed guide strips of cruciform

cross section applied to opposite sides of the wagon box, one of the ribs of each of the cruciform guide strips being notched, a seat supporting frame, a seat mounted thereon, extension plates applied to the seat supporting frame and having the ends thereof slotted to receive the cruciform guide strips, latch bolts slidably mounted upon the extension plates for engagement with the notched ribs of the guide strips to lock the seat supporting frame in an adjusted position, and a main lever having an operative connection with the latch bolts for simultaneously manipulating the same.

In testimony whereof I affix my signature 35 in presence of two witnesses.
